BRASSIÈRE

Irving Gimble and Daniel Musano,
New York, N. Y.

Application July 10, 1953, Serial No. 25,875

Term of patent 3½ years

(Cl. D20—4)

To all whom it may concern:

Be it known that we, Irving Gimble, and Daniel Musano, both citizens of the United States of America, and residents of New York city, county of Queens, and State of New York, have invented a new, original, and ornamental Design for a Brassière, of which the following is a specification, reference being had to the accompanying drawing, forming part thereof, wherein,

Figure 1 is a front perspective view of a brassière showing our new design in closed position.

Figure 2 is a rear elevational view, drawn to a smaller scale.

Figure 3 is a plan view of the brassière shown in Figure 1 in open position showing the inner face thereof.

We claim:

The ornamental design for a brassière, substantially as shown and described.

IRVING GIMBLE.
DANIEL MUSANO.
